ELECTRIC SNAP SWITCH

George J. Meuer, Milwaukee, Wis., assignor to
Cutler-Hammer, Inc., Milwaukee, Wis., a cor-
poration of Delaware

Application November 13, 1936, Serial No. 110,704

10 Claims. (Cl. 200—38)

This invention relates to improvements in electric snap switches.

A primary object of the invention is to provide a novel form of snap switch including a novel form of operating means therefor.

Another object is to provide a snap switch which is particularly adapted for use in conjunction with a known form of clockwork timing mechanism.

10 Another object is to provide a device including a snap switch which is manually operable to closed circuit position and automatically operable to open circuit position upon expiration of a predetermined variable period of time.

15 Another object is to provide a snap switch having stationary and movable contacts of novel form.

Another object is to provide novel mounting means for the stationary and movable parts of 20 the snap switch.

Another object is to provide simple means for guiding the movements of the switch contactors and for limiting the degree of movement thereof in one direction.

25 Another object is to provide a switch adapted for alternative use with binding screws or plug jacks for connection thereof in the controlled circuit.

Another object is to provide a snap switch 30 affording at least six breaks in series in the controlled circuit.

Other objects and advantages of the invention will hereinafter appear.

The accompanying drawings illustrate a preferred embodiment of my invention, and a slight modification of said preferred embodiment, which will now be described—it being understood that the illustrated embodiment is susceptible of change in respect of certain details of construction thereof without departing from the scope of the appended claims.

In the drawings, Figure 1 is a front elevation (actual size) of a preferred form of timing device in conjunction with which my improved snap switch mechanism may be employed.

Fig. 2 is a bottom plan view of a device like that shown in Fig. 1, the same illustrating the manner of attaching the various parts to the insulating base of the switch.

30 Fig. 3 is an enlarged sectional view, on the line 3—3 of Fig. 1, illustrating the operative relationship between the clockwork timing mechanism and my improved snap switch.

Fig. 4 is a view of the inner surface of the insulating base shown in Fig. 2, illustrating the

stationary contact and terminal members, other parts of the switch mechanism being omitted.

Fig. 5 is a fragmentary view similar to Fig. 4, but on an enlarged scale, illustrating the movable elements of the switch mechanism in the 5 circuit interrupting position thereof.

Fig. 6 is a further enlarged fragmentary sectional view, on the line 6—6 of Fig. 5, illustrating one pair of stationary contacts and the contactor adapted for movement into and out of 10 engagement therewith.

Fig. 7 is a fragmentary sectional view of the casing for the complete device, illustrating somewhat schematically the means enabling bodily movement of the timing mechanism along with 15 the central shaft (see Fig. 3) whereby the switch mechanism is operated, and

Fig. 8 is a fragmentary view partly in elevation and partly in vertical section illustrating the manner of substituting plug jacks for the 20 wiring terminal screws shown in Figs. 2 and 3.

Referring first to Figs. 1 to 7 of the drawings, the numeral 10 designates a substantially cylindrical molded hollow member composed of a suitable insulating material, such as that sold 25 commercially under the trade name of "Bakelite". Member 10 forms the main portion of the enclosing casing for a combined switch and clockwork timing mechanism, the character of which is best illustrated in Fig. 3. Member 10 30 is adapted to fit within a substantially circular opening of corresponding size formed in a panel or the like (not shown) to which the same may be attached in any desired manner. Member 10 is provided at its forward end with a flange 11 35 which overlies the aforementioned panel, and said member is provided with an integral lug or projection 12, which cooperates with the walls of a notch formed in the panel opening to restrain said member from rotary displacement. 40

Member 10 is provided adjacent to its forward end with an inwardly extending annular flange 13 (Fig. 3) against which a circular metal plate 14 is adapted to seat; said plate 14 forming the forward end wall of the casing. Member 10 is 45 provided with an integral inwardly extending lug or projection 15 and plate 14 is provided with a notch 16 to accommodate said lug, whereby said plate is restrained from rotary displacement relatively to member 10. Flange 13 and plate 14 50 are offset inwardly from the forward end of member 10 whereby a cylindrical recess 17 is provided. Located within recess 17 and adapted to cover substantially the entire outer surface of plate 14 is a flange or plate 18 formed integrally 55

with the main body portion 19 of a handle member of molded insulating material, a separately molded manually operable insulating knob portion 20 being fitted against the outer end of portion 19.

In practice I prefer to provide the body portion 19 with a pair of diametrically opposed openings or through passages 21 and 22 of circular cross section; and I provide the inner face of knob portion 20 with an integral pair of diametrically opposed projections 23 and 24 of circular cross section which are adapted to fit rather snugly within the outer ends of the respective openings 21 and 22, whereby said knob portion 20 is restrained against rotation with respect to portion 19. Body portion 19 is provided centrally thereof with a passage 25 of circular cross section; said passage having at the inner end thereof of a portion 26 of greater diameter. A machined metal hub member is provided with portions 27 and 28 which are freely insertable into passage 25 and portion 26, respectively.

Rigidly and non-rotatably secured to the inner end of said hub member, in the manner indicated in Fig. 3, is a flat sheet metal plate 29, the opposite ends of which are reduced and bent upwardly at right angles to the main body thereof as indicated at 30 and 31 for reception with a fairly close fit in the inner ends of the aforementioned passages 21 and 22. Said hub member is provided at its upper end with a cylindrical recess 32 to freely accommodate the smooth cylindrical portion 33 of a machined fastening member the flat and slotted head portion 34 of which is adapted to seat within a recess 35 provided in the outer surface of knob 20.

The inner end portion of the hub member 27 is provided with a central opening 36 of polygonal form (preferably square) in cross section to accommodate the shaft portion 37 of corresponding size and shape in cross section, whereby said hub member and the shaft are constrained to rotate with each other. Said shaft is provided adjacent to the portion 37 with a reduced and threaded portion 38 which is adapted for cooperation with the threaded recess 39 in the portion 33 of the fastening member. In this manner the parts aforescribed are interlocked with each other for rotation thereof in each direction with respect to plate 14 and casing member 13. A circular flexible insulating disk 40 (such as Celluloid of the desired color) is inserted with a press fit into the recess 35 in a relation substantially flush with the outer surface of knob portion 20 to provide a more finished appearance of the latter. The periphery of knob 20 is preferably milled or grooved, as best illustrated at 41 in Fig. 1, to facilitate manipulation thereof.

The flange 11 is provided at one point thereof with a non-beveled edge portion 42, which is provided with a V-shaped or arrowhead legend 43 for cooperation with a similar legend 44 (Fig. 1) formed upon the outer surface of flange 18. Flange 18 is provided at legend 44 with a circular opening 45 (Fig. 3) to freely accommodate the cylindrical stud or projection 46 which is rigidly attached to plate 14 in the manner illustrated in Fig. 3; and when these parts are in the respective positions thereof illustrated in Figs. 1 and 3, the shaft comprising portions 37 and 38 is permitted to move to its inner extreme position under the bias of a pair of spring members, one of which is shown at 47 in Fig. 7. Flange 18 is provided in its under surface with an approximately annular groove 48 of channel-shape in

cross section (see Fig. 3). As shown in dotted lines in Fig. 1, one end 49 of groove 48 leads to and ends with the aforementioned opening 45 in flange 18, whereas the other end 50 of said groove is spaced a short distance to the right 5 of said opening 45.

Knob 20 is preferably provided with a curved arrow 51 (Fig. 1) or a similar legend to indicate the direction in which said knob is to be turned manually to set the clockwork mechanism; and 10 said knob is also preferably provided with the legend "Pull out and turn", as indicated at 52, the arrangement being such that when knob 20 is pulled outwardly against the action of the springs (one of which is shown at 47 in Fig. 7), 15 the same may be turned manually in a clockwise direction, with the result that the outer end of pin 46 enters groove 48. The peripheral upper surface of flange 18 is preferably divided into 20 sixty sections, representing sixty minutes, and each five sections are designated by the numerals or legends "5", "10", etc., representing time periods of five minutes, ten minutes, etc. As will be understood from the foregoing the clockwork mechanism is adapted when unrestrained to effect rotation of knob 18, 20 at a rate corresponding to one complete rotation thereof in sixty minutes.

The means for restraining movement of the clockwork mechanism includes the aforementioned pin 46 when engaged with the walls of opening 45 in flange 18. In addition, I prefer to provide a circular flat metal member 53 which is provided centrally thereof with a rectangular opening 54 for slidable but non-rotatable engagement with the rectangular portion 37 of the shaft. A metal tube or ferrule 55 is interposed between the lower end of hub member 27 and member 53, whereby upon tightening of fastening member 34 the member 53 will be held at the 40 lower extremity of shaft portion 37. Member 53 is provided with a peripheral notch 56 (Fig. 3) which is preferably in the radial plane of the opening 45 in flange 18. Rigidly attached to plate 14 and extending from the inner surface 45 thereof in the radial plane of the aforementioned pin 46 is a punched sheet metal member having a lug portion 57 offset inwardly from the inner surface of plate 14 for positioning thereof between the opposed walls of notch 56 in member 53 when the shaft is in its normal or inner extreme position. In this manner rotation of knob 20 in a counterclockwise direction (Fig. 1) by the clockwork mechanism is positively prevented.

However, said metal member is provided between lug 57 and plate 14 with a notch 58 which is adapted to provide rotatable clearance for member 53 (as shown in dotted lines in Fig. 3) when knob 20 is pulled to its outer extreme position. The clockwork mechanism which may be of a known form, is represented by the dotted line rectangle 59 in Fig. 3, and is adapted to move bodily with the shaft upon inward and outward movement of the latter. The clockwork mechanism as a whole is restrained against rotation with respect to the casing parts 10, 14, as by mounting the upper and lower end plates 60 and 61 thereof (Fig. 7) for sliding movement upon a pair of rods or studs, one of which is shown at 62 in said figure. As shown in Fig. 7, the reduced upper ends of said rods (as represented by 62) are adapted to penetrate openings provided in plate 14 and are upset over the outer face of the latter, as indicated at 63,—each rod having a coiled compression spring 47 interposed between 75

plate 14 and the upper end plate 60 to bias said mechanism toward its inner extreme position.

As shown in Fig. 3 the end 64 of the main spring 65 of the clockwork mechanism is rigidly attached to an intermediate portion 66 of the shaft, as by means of a pin or rivet 67. From the foregoing description it will be apparent that, with the parts in the positions thereof shown in Figs. 1 and 3, upon a predetermined degree of outward pull upon the knob 20, 18 said knob may be rotated in a clockwise direction (Fig. 1) to preselect a desired time period of operation of the clockwork mechanism. If a ten minute period is selected the legend "10" upon the flange 18 will be registered or aligned with the arrow-head or similar legend 43 formed upon the aforementioned flange 11.

I utilize such extreme outward movement of the shaft to effect operation of a snap switch mechanism to closed circuit position. Said switch mechanism as shown is of the push-pull type, and the same comprises essentially a double-cone cam member 68, preferably formed of metal, the annular high point of said cam being designated by the numeral 69 in Fig. 3. Cam 68 is secured to a reduced lower end portion 70 of the shaft in a manner to permit rotation of the shaft with respect to the cam while restraining said parts against axial movement relatively to each other. The securing means for said parts preferably comprises a washer 71 which overlies the lower end of member 68, said washer being secured against endwise displacement as by upsetting or riveting thereover the extreme lower end of the shaft, as indicated at 72.

Surrounding cam member 68 is a coiled tension or garter spring 73 which automatically moves with a snap action to one side or the other of the high point 69 of the cam, according to the direction of movement of the latter. Spring 73 is held captive between the upper surface of a substantially circular punched insulating plate 74 and the lower surface of a sheet metal plate 75 which has arms 76, 77 and 78 bent downwardly at substantially right angles to the plane thereof, said arms having reduced lower ends which penetrate suitable openings provided in plate 74 and are bent inwardly over the lower surface of the latter, as shown at 79.

Plates 74 and 75 are respectively provided with centrally located circular openings 80 and 81 to provide clearance for cam member 68. As shown in Figs. 3 and 5 the degree of upward movement of plate 74 is limited by engagement of the upper surface thereof with the flat lower surfaces of the heads of three posts 82, 83 and 84, the lower ends of which are upset over the lower surface of the insulating switch base 85 in the manner indicated at 86 (post 82). Plate 74 is provided in its periphery with segmental notches as shown in dotted lines at 87, 88 and 89 in Fig. 5 to accommodate the intermediate cylindrical portions of posts 82, 83 and 84, whereby said plate 74 is restrained against rotary movement and tilting thereof to a substantial degree is prevented.

Positioned below the surface of insulating plate 74 are three substantially circular bridging contactors 90, 91 and 92, the same being equidistantly spaced from the respective posts 82, 83 and 84. Said bridging contactors are preferably punched from a sheet of composite metal and stamped to the form thereof best illustrated at 90 in Fig. 6. Said composite metal is preferably approximately one-fiftieth of an inch thick, the upper half 90a of said thickness preferably con-

sisting of hard copper and the lower half 90b thereof preferably consisting of fine silver. Each contactor is provided with a central opening 93 to freely accommodate the intermediate portion 93 of a pin or rivet the head 94 of which is received within an upward depression formed in said contactor.

The reduced upper end 95 of each pin is adapted to penetrate an opening provided in plate 74 and is upset over the upper surface of the latter, as indicated at 96 in Figs. 3 and 6, a metal washer 97 being preferably interposed between and clamped by the plate 74 and the shoulder formed by the portion 93 of the pin. By this arrangement each contactor (such as 90) is free to move upwardly and downwardly to a limited extent upon the portion 93 of the pin and to tilt with respect thereto, to provide for a substantial degree of self-adjustment of the contactors with respect to the stationary contacts of the switch.

The stationary contacts of the switch preferably consist of the flat heads of rivets formed of fine silver and arranged in pairs, as best illustrated at 98, 99; 100, 101; and 102, 103 in Fig. 4, for cooperation with the respective contactors 90, 91 and 92 (see dotted line illustration in Fig. 5). Contact 98 is rigidly attached to a terminal plate 104 of the form illustrated in Fig. 4, the manner of attaching said contact being shown at 98a in Fig. 6. Terminal plate 104 is preferably attached to base 85 as by means of a pair of rivets 105 and 106, the heads of which are shown in Fig. 2. Plate 104 is further provided with a tapped opening 107 to receive the threaded shank of a binding screw 108, which extends upwardly through a clearance opening provided therefor in base 85.

Contacts 99 and 100 are attached to a terminal plate 109, and the latter is attached to base 85 as by means of rivet 110, the binding screw 111 when threaded into the opening 112 assisting in preventing displacement of plate 109 with respect to base 85. Contacts 101 and 102 are attached to opposite ends of a plate 113, which is secured to base 85 by a rivet 114, a pair of studs 115, 116 being formed on base 85 to restrain plate 113 against rotary displacement. Contact 103 is attached to one end of a terminal plate 117, which is secured to base 85 by rivets 118 and 119, said terminal plate having a tapped opening 120 to receive the threaded shank of binding screw 121.

The complete device herein described is particularly applicable to control of the duration of the time for supplying electrical heat in so-called permanent waving devices used by hairdressers. Assuming connection of two circuit wires to the respective binding screws 108 and 121, it will be apparent that upon snap operation of the switch to circuit interrupting position the contactors 90, 91 and 92 will be raised simultaneously to provide six breaks in series between the binding screws 108 and 121. Binding screw 111 provides for connection of one terminal of a voltmeter with respect to the controlled circuit. The form, composition and arrangement of the stationary contacts are such as to provide a relatively high current carrying and controlling capacity of the switch as a whole, while insuring a relatively long life for the switch parts.

The switch base 85 (Figs. 3 and 4) is provided with an upstanding annular flange 122 of a size to fit within the lower end of casing member 10, said base having integral upstanding lugs 123 and 124 which are drilled and tapped, as indicated at 125 and 126, in alignment with radial openings 75

127 and 128 provided in member 10 to receive the shanks of screws 129 and 130 whereby said parts are secured to each other. Base 85 is preferably further provided with tapped recesses 131 and 132 for the reception of screws or bolts (not shown) whereby the unit as a whole may be retained in position with respect to the aforementioned panel or similar support.

As shown in Fig. 7 the pair of bolts (one of which is shown at 62) are provided at their lower ends with reduced and threaded ends 133 and 134 (Fig. 2) which penetrate corresponding openings in base 85 and are secured to the latter by nuts 135 and 136 rotatably received in recesses in the lower surface of said base.

In Fig. 8 I have shown a slight modification wherein a plug jack member 137 is substituted for each of the binding screws 103, 111 and 121 aforementioned. Each plug jack is provided with a threaded shank 138 for cooperation with the tapped openings provided in the respective terminal members, such as 104; and as indicated at 139 the inner ends of the threaded shanks are upset over the respective terminal members to rigidly and permanently connect the same. With the device modified in the manner illustrated in Fig. 8 any one of a number of heating devices may be plugged onto the timing device herein described, by merely providing the several heating devices with female plug connectors for cooperation with the set of plug jacks, such as 137.

As shown in Fig. 3, base 85 is provided centrally thereof with a circular recess 140 to accommodate one end of cam member 68 and to limit the degree of inward movement of the latter. An opening 141 which communicates with recess 140 is adapted to afford clearance for washer 71 and the upset end 72 of the shaft. If desired, of course, a sub-recess corresponding in diameter with opening 141 might be provided, a diaphragm integral with base 85 being provided at the rear face of the latter, to render the complete casing substantially dust-tight.

While I have shown the switch parts as arranged to provide six breaks in series in the circuit to be controlled thereby, it is to be understood that various other arrangements of switch parts may be provided. For instance, by providing terminal members individual to the respective stationary contacts of each set, a switch adapted to control three separate circuits may be produced. Various other modifications will at once suggest themselves to those skilled in the art.

What I claim as new and desire to secure by Letters Patent is:

1. In a device of the character described, in combination, a casing, a clock-spring operated timing mechanism carried by said casing, a reciprocal and rotatable shaft engaged with said mechanism for rotation by the latter in one direction, a knob rigidly attached to said shaft at one end of the latter, said knob and said casing having cooperating legends formed thereon to indicate the relative rotary positions thereof, spring means for biasing said knob and said shaft inwardly with respect to said casing, cooperating means on the upper surface of said casing and on said knob to provide for extreme inward movement of the latter in only one rotary position thereof, said knob providing for outward movement of the same and of said shaft against the bias of said spring means whereby said knob and said shaft may be set at will in a given rotary position with respect to said casing, a push-pull switch mechanism associated with said shaft and

having a plurality of bridging contactors resiliently biased jointly to one extreme position thereof or the other, and means for effecting snap operation of said bridging contactors jointly to closed circuit and open circuit positions thereof upon outward and inward movements respectively of said shaft.

2. In a device of the character described, in combination, a casing, a clock-spring operated timing mechanism carried by said casing, a reciprocal and rotatable shaft engaged with said mechanism for rotation by the latter in one direction, a knob rigidly attached to said shaft at one end of the latter, said knob and said casing having cooperating legends formed thereon to indicate the relative rotary positions thereof, spring means for biasing said knob and said shaft inwardly with respect to said casing, cooperating means on the outer surface of said casing and said knob to provide for extreme inward movement of the latter in only one rotary position thereof, said knob providing for outward movement of the same and of said shaft against the bias of said spring means whereby said knob and said shaft may be set at will in any desired rotary position with respect to said casing, a push-pull switch mechanism associated with said shaft, means for effecting snap operation of said switch mechanism to closed circuit and open circuit positions thereof upon outward and inward movements respectively of said shaft, said last mentioned means comprising a double-cone cam attached to said shaft at the inner end thereof, a garter spring encircling said cam, a cage for said spring, a relatively thin, flat insulating plate attached to said cage, a plurality of bridging contactors carried by said insulating plate, and a plurality of pairs of stationary contacts into and out of engagement with which said contactors are adapted to move.

3. A time controlled switching device, comprising a casing, a clock mechanism carried by said casing, said casing having indicating means formed thereon at the front face thereof, said casing having portions of said front face located in different planes, a shaft member extending inwardly through said front face of the casing, spring means engaged with said shaft to bias the same to its inner extreme position, a knob attached to the outer end of said shaft, said knob having indicating means formed thereon for cooperation with the indicating means aforementioned, a projection at the front face of said casing and a cooperating recess in said knob to provide for extreme inward movement of said shaft under said bias in only one rotary position of said knob, said projection and said knob cooperating in other rotary positions of the latter to prevent inward movement of said shaft under said bias, and a push-pull snap switch mechanism operable by said shaft to make and break circuit with a snap action upon outward and inward movements respectively of the latter.

4. In an electric snap switch, in combination, an insulating base having a substantially central recess formed therein, a plurality of pairs of stationary contacts located upon one face of said base and secured thereto in symmetrical relationship to said recess, a plurality of terminal members, said terminal members being electrically and mechanically connected with certain of said contacts, certain contacts of the several pairs being electrically and mechanically connected with each other, a flat plate of insulating material overlying said pairs of stationary contacts, a num- 75

ber of bridging contactors interposed between the respective pairs of contacts and said plate and supported by the latter with a predetermined degree of lost motion, said plate having a plurality of notches formed in the periphery thereof, a corresponding number of studs secured to said base and cooperating with the walls of said notches to assist in guiding said plate and to restrain the latter against rotation relatively to said base, said 5 studs having heads formed thereon to limit the degree of movement of said plate away from said base, a frame member secured to said plate, said plate and said frame member having openings formed therein in alinement with said base recess, 10 a garter-spring positioned between said plate and said frame member, a double-cone cam member having the portion of greatest diameter at a point intermediate the length thereof, said cam member being adapted upon movement thereof to each 15 extreme position to effect movement of said plate in the opposite direction with a snap action through the medium of said spring, and means comprising a rod rigidly attached to said cam member to provide for movement of said parts 20 in the manner aforescribed.

5. In an electric snap switch of the push-pull type, in combination, an insulating base, a plurality of sets of stationary contacts secured to one surface of said base, a flat plate of insulating material positioned above said sets of contacts, a plurality of flat substantially circular contactors supported by said plate in a manner to provide for rotation and a predetermined degree of tilting movement of the former with respect 30 to the latter, said contactors being movable jointly by said plate into and out of engagement with the respective sets of contacts, said plate and said base having cooperating means to restrain the former against rotation with respect to the latter 35 and to limit the degree of movement of said plate away from said base, a metal frame member positioned upon and secured to the surface of said plate remote from the contacts, said plate and said frame member having alined openings 40 formed therein, a double-cone cam member movable through said openings, a garter spring surrounding said cam member and positioned between said plate and said frame, said spring cooperating with said plate and said frame member 45 to effect snap movements of said plate to opposite extreme positions thereof upon reciprocating movement of said cam member in reverse directions respectively, means including a member attached to said cam member for effecting reciprocating movements of the latter in reverse directions respectively, and associated means for limiting the degree of reciprocating movement of said cam member in each direction.

6. In a device of the character described, in combination, a contactor carrier for electric snap switches of the push-pull type, said carrier comprising a substantially circular flat punched plate of insulating material, a metal frame member positioned upon the upper surface of said plate, 60 said plate and said frame member having alined openings formed therein to provide clearance for a cam member of the double-cone type, a garter spring held captive between said plate and said frame member and adapted to surround said cam member in all positions of the latter, said base 65 having guiding means associated therewith and said plate being formed at the periphery thereof for cooperation with said guiding means, and a plurality of bridging contactors carried by said 70 plate at the lower surface thereof and tilttable

with respect thereto, said contactors being adapted for cooperation with sets of contacts of suitable form.

7. In a device of the character described, in combination, a contactor carrier for electric snap switches of the push-pull type, said carrier comprising a substantially circular flat punched plate of insulating material, a metal frame member positioned upon the upper surface of said plate, said plate and said frame member having alined openings formed therein to provide clearance for a cam member of the double-cone type, a garter spring held captive between said plate and said frame member and adapted to surround said cam member in all positions of the latter, said base 5 having vertical guiding means associated therewith and said plate having a plurality of notches formed in the periphery thereof for cooperation with said guiding means, said plate having a plurality of symmetrically arranged studs rigidly attached thereto at points spaced inwardly from the periphery thereof, each stud having a head portion projecting downwardly from the lower surface of said plate, and a corresponding number of bridging contactors rotatably and tiltably supported by said head portions for cooperation with sets of stationary contacts of suitable form.

8. In a device of the character described, in combination, a contactor carrier for electric snap switches of the push-pull type, said carrier comprising a substantially circular flat punched plate of insulating material, a metal frame member positioned upon the upper surface of said plate, said plate and said frame member having alined openings formed therein to provide clearance for a cam member of the double-cone type, a garter spring held captive between said plate and said frame member and adapted to surround said cam member in all positions of the latter, said plate 10 having a plurality of notches formed in the periphery thereof for cooperation with guiding means of suitable form, said plate having a plurality of symmetrically arranged studs rigidly attached thereto at points spaced inwardly from the periphery thereof, each stud having a head portion projecting downwardly from the lower surface of said plate, a corresponding number of bridging contactors rotatably and tiltably supported by said head portions for cooperation with sets of stationary contacts of suitable form, each 15 of said contactors comprising a punched and stamped disk of composite sheet metal, the lower surface of each disk consisting of a layer of silver and the upper surface of each disk consisting of a layer of copper.

9. As an article of manufacture, a bridging contactor for electric snap switches of the push-pull type, said contactor consisting of a punched and stamped composite metal member of substantially circular contour, said member having a centrally located circular depression formed therein and opening to the lower surface thereof, said member having a central opening of circular contour within the area of said depression, said depression and said opening being respectively 20 adapted to accommodate the head and shank of a supporting member of suitable form, the lower portion of the thickness of said metal member consisting of silver, and the upper portion of such thickness consisting of copper.

10. In a device of the character described, in combination, a clockwork timing mechanism, a casing enclosing the same, a shaft located within said casing and having a portion projecting from the forward face of the latter, said shaft being 25

3
rotatable and reciprocable with respect to said casing, a manually operable knob rigidly attached to the projecting portion of said shaft, spring means normally biasing said shaft toward its inner extreme position, cooperating means on said knob and said casing at the outer surface of the latter to restrain said shaft against inward movement under said bias except in one rotary position thereof, a spring associated with said clock-work mechanism and said shaft to be tensioned by the latter upon rotation thereof in one direction, associated means including the aforementioned restraining means for restraining said shaft against rotation pending movement thereof to its outer extreme position against said bias, said spring acting to return said shaft to said

one rotary position thereof within a predetermined period of time depending upon the degree of manual rotation of said knob, said shaft when so returned being movable by said spring means to its inner extreme position, means associated with said casing and said knob to indicate the time period selected by adjustment of the latter, an electric snap switch of the push-pull type associated with said shaft at the inner end of the latter, said switch being operable by said shaft to closed circuit position upon movement of the latter to its outer extreme position, and said switch being operable by said shaft to open circuit position upon movement of the latter to its inner extreme position. 15

GEORGE J. MEUER.
